COAXIAL CABLE WITH HELICAL
INSULATION

Thomas J. Rhodes, Ramsey, N. J., assignor to
United States Rubber Company, New York,
N. Y., a corporation of New Jersey

Application January 2, 1947, Serial No. 719,868

2 Claims. (Cl. 174—29)

1

This invention relates to electric cable, and more particularly to coaxial cable for the transmission of high frequency current.

In certain types of coaxial cable constructions now on the market the outer tube or braid of conductive material forming the outer conductor of the cable is supported upon and held in spaced concentric relationship with the inner conductor by a series of disc-type spacers located along the length of the inner conductor at spaced intervals. Since the main dielectric material in such a cable is air, the cable exhibits exceptionally low loss characteristics. However, there is a tendency for the spacers to become displaced whenever the cable is subjected to bending so that the concentricity of the inner and outer conductors is not maintained which adversely affects the electrical characteristics of the cable. Moreover, the method of manufacturing such a cable is rather costly inasmuch as the spacers must be first placed on the wire and then held in position during assembly of the outer conductor. Thus, this type of coaxial cable has found favor chiefly due to the air dielectric which gives it low loss characteristics. But it is open to the objection that it is relatively high in cost and there is considerable danger that the electrical characteristics of the cable may vary at the points where the cable is bent.

In another type of high frequency coaxial cable on the market the dielectric material comprises a solid or sheeted plastic, such as polyethylene, surrounding the inner conductor and on which the outer conductor rests. Since the outer concentric conductor is supported at every point along its length by the plastic dielectric material this cable has the advantage that it is not subject to distortion upon bending so that the electrical characteristics of the cable are not impaired at those points. Moreover, the extruding process by which the dielectric material is applied to the inner conductor may be performed quickly and at low cost. However, a considerable amount of the plastic dielectric material is required per unit length of cable thereby making the cable more rigid and increasing its weight with a corresponding increase in material cost.

According to the present invention, however, a coaxial cable is provided which embodies the advantages of each type of cable without the corresponding disadvantages. For example, the cable is one which essentially employs air, or other suitable gas, as a dielectric along its entire length but in which a supporting structure or web is provided for maintaining the inner and outer

2

conductors in concentric relationship. The supporting structure is obtained by means of a special extruding process which lends itself to high speed operation whereby the cable may be manufactured in any desired length at comparatively low cost. Moreover, the construction makes possible a considerable saving in material. The web or supporting structure is so designed as to maintain the inner and outer conductors in concentric relationship irrespective of any bends or twists to which the cable may be subjected during installation.

Therefore, it is an object of the invention to provide a new and improved coaxial cable which has exceptionally low loss characteristics.

It is another object of the invention to provide a new and improved coaxial cable so constructed as to give excellent flexibility without displacement of the conductors making it suitable for use in a wide variety of installations.

It is still another object of the invention to provide a new and improved core for use in coaxial cable constructions, the core providing a means whereby accurate and permanent alignment of the inner conductor is obtained under all normal conditions of use.

In the accompanying drawing, Fig. 1 illustrates part of the cable constructed in accordance with my invention showing one suitable method of 30 making the cable; Fig. 2 is a side view of a guide die utilized in performing the method; Fig. 2a is an end view, and Fig. 2b is a perspective view of such die; Fig. 3 is a cross-sectional view through the cable core taken along the line 3—3 of Fig. 1; 35 Fig. 4 and Fig. 4a illustrate cross-sectional views of modified forms of cable constructions; and Fig. 5 is a view, partly in section, of a coaxial cable constructed in accordance with the present invention.

Referring to the drawing, Fig. 5 illustrates a coaxial cable constructed in accordance with my invention and which includes an inner conductor 1, a concentric sleeve 2 of insulating material supported on a web 3 twisted around the inner conductor, and an outer conductor 4 supported on the insulating sleeve 2. It will be seen that the space between the inner conductor 1 and the sleeve 2 forms an air chamber 5 extending along 45 the length of the cable and providing a substantially uniform air dielectric medium between the inner and outer conductors except for the small amount of space taken up by the web 3. The inner conductor 1, sleeve 2, and web 3 form, in effect, a cable core 6 which may be made in any

desired length by means of an extruding process to be described below.

Fig. 1 also illustrates the cable core 8 which has just been formed by an extruding machine 7. In the illustration, the extruding machine 7 has been shown in schematic form with only its essential elements, inasmuch as it forms the subject matter of my United States Patent No. 2,465,482 issued March 29, 1949. It includes a tubing head 8 provided with a chamber 9 for receiving a rotating feed screw 10. Plastic insulating material, such as polyethylene or polystyrene, enters the tubing head through an inlet port 11 and is forced through the head to a nozzle 12 by means of the helical feed screw 10. The plastic insulating material is then forced outwardly through an annular orifice 13 in the nozzle 12 around the center conducting wire 1 in a manner now to be described. Since the insulating material is thermoplastic, it is heated to plastic condition before being extruded, and it then solidifies on leaving the tube.

The inner conductor 1 is drawn continuously through the lower end of the tube in which position it is centered in the orifice 13. The wire extends through a rotating guide die 14 having an enlarged head 15 which likewise is centered in the orifice 13. The walls of the head 15 and nozzle 12 cooperate to form the annular orifice 13 through which the insulating material is extruded to form the sleeve 2. In order to form the web 3 which supports the sleeve 2 on the inner conductor, the head 15 of the die is provided with an angularly disposed slot 16 which extends from the outer wall of the head to an inner bore 17 in the die through which the wire 1 travels. It will be seen that, as the wire 1 is drawn through the tube during the extruding operation, a portion of the plastic material will travel through the slot 16 to form the supporting web 3. Inasmuch as the slot 16 is formed in the wall of the head 15, the web 3 will be formed integrally with the sleeve 2. Also, since a portion of the plastic material flows through the slot 16 into the opening of the bore 17, a small amount of the plastic material will be forced outwardly from the opening 17 around the wire 1 thereby firmly anchoring the web 3 to the inner conductor 1, in the manner indicated at 18 in Fig. 3.

The die 14 is rotated during the extruding operation by means of a drive wheel 19. In this way the web 3 is formed as a helicoid around the length of the wire 1 as it travels through the extruder. Since it encircles or extends around the wire it supports the outer insulating sleeve 2 continuously along the length of the wire. This means that the wire 1 is firmly supported centrally of the sleeve 2 throughout its entire length. The thin film of insulating material 18 which surrounds the wire 1 prevents the web 3 from pulling away from the wire when the cable is subjected to bending during use. It will be apparent that the spacings of the convolutions of the helicoid web 3 will be determined by the speed at which the die 14 is rotated during the extruding operation, relative to the linear speed of the wire. Hence, if it is desired to increase the number of turns of web 3 per unit length of cable, it is simply necessary to increase the speed of rotation of the die 14.

In constructing the die 14 it is important that the dimensions of the slot 16 be so related to the dimensions of the annular orifice 13 that the material forming the web and the material

forming the sleeve shall issue from the extruder head at substantially the same linear rate. For this purpose it is found in practice that the opposing walls of the slot 16 should be spaced apart by a distance substantially the same as or slightly greater than the radial width of the annular orifice 13. It is then found that the thickness of the extruded web is about equal to the wall thickness of the sleeve, and that the extruded sleeve is of uniform cross-section with a smooth true outer surface. If an excess of material flows through the slot 16, as in the event that the slot 16 is made too large, a helical ridge will form along the length of the sleeve 2 at the line of juncture of the web 3 with the sleeve. Conversely, if the rate of flow is too small, as in the event that the slot is too narrow, there will be a tendency for the sleeve 2 to be drawn inwardly toward its axis, resulting in a helical depression being formed along the line of juncture of the sleeve 2.

When the cable core is extruded in extremely long lengths there is some likelihood that a partial vacuum may be formed in the chamber 5 between the wire 1 and the outer sleeve 2, which might result in some collapse or distortion of the sleeve. The tendency toward forming a vacuum will be considerable, unless means are provided to introduce air, or other gaseous dielectric medium, into the interior of the core during the extruding operation. To this end, the die 14 is provided with an extension 20 for cooperating with an air supply pipe line 21. A combined coupling and packing 22 seals the pipe line to the die and at the same time provides a means of permitting rotation of the die 14 relative to the gas supply pipe 21. The bore 17 extending through the die is made slightly larger than the diameter of the conductor 1 so that the conductor may be easily pulled therethrough, but it is small enough to serve as a guiding means for the conductor as it travels through the extruder. As thus constructed, the bore is still large enough to provide for a flow of air along the length of the die 14 to an opening 23 formed in the head 15 of the die. The opening or passageway 23 extends at an angle to the bore 17 and opens upon the interior of the channel 2 as the sleeve is extruded from the orifice 13.

During the extruding process, air or other dielectric gas such as nitrogen, at a pressure equal to or slightly above atmospheric, is forced along the length of the die 14, in the manner described, to the interior of the sleeve 2. In addition to providing an insulating medium within the cable, the gas pressure serves to maintain the cylindrical configuration of the sleeve 2. If a lowering of the gas pressure occurs within the core, there is a tendency for the sleeve 2 to be drawn inwardly toward the wire due to the difference in pressure between the outside and the inside of the sleeve. This tendency is overcome by introducing the gas under a pressure equal to or slightly above atmospheric to the interior of the sleeve so as to overcome any tendency of the sleeve to collapse. It should be noted that the pressure of the gas supplied to the interior of the sleeve through the orifice 23 should be carefully regulated to assure a uniform product. If the pressure of the gas introduced to the interior of the core is too high there is a tendency for the side walls 2 of the sleeve to expand thereby producing a core of uneven configuration. The gas pressure within the sleeve 2 may be more closely regulated during actual

manufacture if, at the outset of the manufacturing run, the end of the sleeve 2 is sealed down around the conductor 1 to close the end of the core to prevent the escape of air.

It has been found during actual manufacture that the quality of the product can be maintained uniform and the manufacturing process speeded up if air is supplied to the interior of the core in the manner indicated. In this way, the sleeve 2 is formed as a smooth uniform dielectric covering around the wire 1. Although, the use of the air feed greatly facilitates production, it should be manifest that in certain instances the air feed may be omitted. For example, if low extruding speeds are used together with a quick-setting thermoplastic insulating material, it is possible to extrude the sleeve and have it set in position without distortion without the use of the air supply.

After the core 6 has been formed in the manner indicated, it may be wound on a reel for further processing or it may be passed directly to a conventional braiding machine for application of the outer braid 4. It should be manifest that other forms of outer conductors may be used, for example, a thin copper sleeve or tape may be wrapped around the core in a manner well understood in the art. Also, the core may be sprayed or painted with a metallic covering directly on the exterior of the sleeve 2.

In the cable construction thus far described, a single helicoidal web 3 is formed about the conductor and within the sleeve. The advantage of this construction is that a minimum amount of material is required to support the sleeve 2, and the sleeve is held in spaced concentric relationship with the inner conductor 1 throughout its length. However, in certain instances, particularly where large diameters of sleeves 2 are required, it may be desirable to extend the web 3 completely across the sleeve in the form of a diametrically disposed web 24, as indicated in Fig. 4. In other instances three or more webs may be used as indicated in Fig. 4a. The various forms of the webs are constructed by providing additional slots in the rotating die plug 14, preferably with equiangular spacing about the axis.

A cable constructed in accordance with my invention is one which gives unusually low capacitance and attenuation as compared with a coaxial cable having a solid dielectric between the inner and outer conductors. Moreover a considerable saving in material is obtained, and the cable is of light weight. At the same time, the two concentric conductors are maintained in accurately spaced relationship with each other throughout the entire length of the cable due to the continuous supporting action of the sleeve 2 and web 3. Thus, when the cable is subjected to twists and bends during installation, the web 3 prevents displacement of the inner conductor 1 relative to the outer conductor, due to the fact that the portion 18 of the web completely surrounds the conductor and prevents it from pulling away from the web. Since the web extends continuously along the length of the cable the inner conductor is supported at every point, which would not be the case if it were supported on spaced insulating disks. The sleeve 2 forms

an accurately located and continuous support for the outer conductor 4 thereby providing a cable having good uniform electrical characteristics throughout its entire length, particularly in those installations in which the cable is bent in sharp angles.

Another advantage of the construction is that by twisting the web around the center conductor, the flexibility of the cable is greatly increased over constructions in which the webs extend in a single plane parallel to the center conductor. Also, the center conductor is supported at every point along its length irrespective of the direction in which the cable is bent.

Although my cable construction is one which is particularly well suited for the transmission of high frequency current it is not necessarily limited to such use. It may be used in the transmission of all types of electric currents wherever applicable.

Having thus described my invention what I claim and desire to protect by Letters Patent is:

1. In a cable for transmission of high frequency current, a flexible conductor, a surface coating of plastic insulating material extending along the length of and covering said conductor, an outer continuous tubular sleeve of plastic insulating material spaced from said conductor and extending along the length thereof, and a helicoidal web of plastic insulating material twisted around and extending along the length of said conductor between said coating and said sleeve, said web being formed integrally with both said coating and said sleeve along their lengths to hold said insulating sleeve in spaced concentric relationship with said conductor.

2. A cable for transmission of high frequency current comprising an inner flexible conductor, a surface coating of plastic insulating material extending along the length of and covering said conductor, an outer continuous tubular sleeve of plastic insulating material spaced from said conductor and extending along the length thereof, a helicoidal web of plastic insulating material twisted around and extending along the length of said conductor between said coating and said sleeve, said web being formed integrally with both said coating and said sleeve along their lengths to hold said insulating sleeve in spaced concentric relationship with said inner conductor, and an outer conductor carried by said sleeve.
